UNITED STATES PATENT OFFICE

2,579,083

DISPENSING DEVICE

Lloyd M. Kramer, Brainerd, Minn.

Application June 11, 1949, Serial No. 88,431

2 Claims. (Cl. 222—437)

1

My invention relates, generally, to dispensers for granular material and more specifically to dispensers of the type which may be used to dispense predetermined amounts of granular or powdered material.

An important object of my invention is the provision of a dispenser as set forth which may be opened to dispense granular or powdered material in various predetermined relatively-accurate amounts, and which may be closed to prevent leakage of material therefrom or ingress thereto of dust, insects, etc.

Another object of my invention is the provision of a dispenser as set forth which is inexpensive to manufacture, easy to operate, and which is extremely durable in use.

Generally stated, my invention consists of the novel devices, combinations of devices, and arrangements of parts hereinafter described and defined in the claims.

In the accompanying drawings, like characters indicate like parts throughout the several views.

Referring to the drawings:

Fig. 1 is a view in perspective of a preferred embodiment of my invention;

Fig. 2 is a vertical section taken substantially on the line 2—2 of Fig. 1;

Fig. 3 is a vertical section taken on the line 3—3 of Fig. 1;

Fig. 4 is a view in side elevation with some parts broken away and some parts shown in section of my novel dispenser illustrating its use in measuring an amount of material to be dispensed;

Fig. 5 is a view corresponding to Fig. 4, but showing a different position of some of the parts;

Fig. 6 is a view corresponding to Figs. 4 and 5, but showing my device in a position to discharge granular material therefrom; and

Fig. 7 is a fragmentary view corresponding to Fig. 5, but illustrating the modified form of the invention.

Referring with greater particularity to the preferred embodiment of my invention illustrated in Figs. 1 to 6, inclusive, the numeral 1 indicates in its entirety a generally rectangular open-topped container having side walls 2 and 3, opposite end walls 4 and 5, and a bottom 6. The open top of the container is normally closed by a cover 7. The container 1 and cover 7 are preferably made from synthetic resins, but may also be made from other suitable materials, such as wood or metal.

The opposite side walls 2 and 3 are internally

grooved to provide channels 8 in upwardly spaced parallel relation to the bottom 6 and which slidably receive a partition 9. A transversely-extending groove or channel 10 in the end wall 4 and in the plane of the channels 8 is adapted to receive the inner end of the partition 9. The partition 9 divides the container 1 into an upper or storage chamber 11 and a lower or dispensing chamber 12, and extends laterally outwardly of the opposite end wall 5 which terminates at the level of the channels 8 with its lower end abutting the upper surface of the partition 9. It will be seen by reference to Figs. 2, 4 and 5 that the open end of the dispensing chamber opposite the end wall 4 provides a discharge opening 13. This opening 13 is normally closed by a depending flange 14 integrally formed with the partition 9 and which is perforated as indicated at 15 (see Fig. 1). I provide suitable means for grasping partition 9 to move the same, such as outwardly projecting ears or the like 16 on the depending flange 14. It is important to note that when the flange 14 is in abutting engagement with the container and closing the discharge opening 13, 25 that the inner end of the partition 9 is received within the channel 10 and the dispensing chamber 12 is sealed off from the storage chamber 11 thereby.

Rigidly secured to the partition 9 by means 30 of a rivet or the like 17 is a rearwardly declining arm 18 which terminates in a wall element 19. The wall element 19 extends the entire width of the dispensing chamber 12 and declines toward the end wall 14 of the container 1 with its lower edge in contact with the bottom 6. Preferably and as shown, the wall element 19 is disposed in the dispensing chamber 12 adjacent the inner end of the partition 9. The upper edge portion of the sloping wall element 19 is spaced 35 from the partition 9 to provide a passage therebetween for the flow of material.

With the cover 7 removed, the storage chamber 11 may be filled with sugar, flour or other material to be dispensed, and the cover replaced. 40 In the drawings, A indicates the granular material in the container. When it is desired to use a given amount of the contents, the partition 9 is moved laterally outwardly a predetermined distance, as indicated in Fig. 4. Material A flows from the storage chamber 11 to the dispensing chamber 12 through the aperture formed by the outward movement of the partition 9. As shown, only a limited amount of the material A can flow through the aperture. Some of the 45 granular material lodges against the sloping wall

19 and is prevented thereby from being displaced by material thereabove. The sloping wall 19 thus aids substantially in obtaining an accurately measured amount of the granular material. When the granular material has stopped flowing through the aperture between the chambers, the partition 9 is slidably moved to close said aperture. The material A in the dispensing chamber 12 is then discharged through the perforations 15 as indicated in Fig. 6. Obviously, when the partition 9 has been moved to close the aperture between the chambers 11 and 12, no material can escape from the chamber 11 while that in the chamber 12 is discharged from the container 1.

In the modified form of the invention illustrated in Fig. 7, parts identical to those of Fig. 1 to 6 inclusive are indicated by like characters with prime marks added. The slideable partition 9' thereof terminates outwardly of the end wall 5' in an angularly disposed handle member 29. This form of the invention provides for an unrestricted discharge opening 13' and is particularly useful when the granular material A' consists of granulated sugar or the like.

The advantages of my invention are especially significant when the device is used by diners in restaurants and the like, in that use of a spoon to ladle out the material is rendered unnecessary; and flies, dust and the like are excluded from contact with said material.

My invention has been thoroughly tested and found to be adequate for the accomplishment of the objectives set forth, and while I have disclosed a preferred embodiment and a single modification of my device, it will be understood that the same is capable of further modification without departure from the scope and spirit of the invention as defined in the claims.

What I claim is:

1. A dispenser for granular material comprising a generally rectangular container, a sliding partition in the lower portion of said container dividing the same into an upper storage chamber and a lower dispensing chamber, the outer end of said partition extending laterally-outwardly through one wall of said container and the inner end of said partition in cooperation with the

opposite wall of said container providing a communicating aperture between said storage and dispensing chambers upon outward sliding movements of said partition, said container providing a discharge opening below the outwardly-projected end of said partition, the extreme outer end of said partition being downturned to provide a closure for said discharge opening when said partition is moved to close the aperture between the storage and dispensing chambers, and a sloping wall scoop element carried by the partition and disposed in the dispensing chamber adjacent the inner end of the partition to limit the flow of material from the storage chamber.

2. A dispenser for granular material comprising a generally rectangular container, a sliding partition in the lower portion of said container dividing the same into an upper storage chamber and a lower dispensing chamber, the outer end of said partition extending laterally outwardly through one wall of said container and the inner end of said partition in cooperation with the opposite wall of said container providing a communicating aperture between said storage and dispensing chambers upon outward sliding movements of said partition, said container providing a discharge opening below the outwardly-projected end of said partition, the extreme outer end of said partition being downturned to provide a closure for said discharge opening when said partition is moved to close the aperture between the storage and dispensing chambers, said closure-forming downturned end of said partition wall being provided with perforations to permit sifting of granular material therethrough.

LLOYD M. KRAMER.
